(57) **CLAIM**

The ornamental design for a pelvic floor exerciser, as shown and described.

DESCRIPTION

FIG. 1 is a perspective view of a pelvic floor exerciser showing my new design from the forward end and two adjacent sides;

FIG. 2 is a perspective view thereof shown from the rearward end and two adjacent sides opposite the sides shown in FIG. 1;

FIG. 3 is an exploded perspective view thereof similar to FIG. 2, shown with the end cap at the rearward end removed; FIG. 4 is a side elevation view thereof shown from one side; FIG. 5 is a cross sectional view taken along line 5-5 of FIG. 4. FIG. 6 is a side elevation view thereof, rotated 45 degrees from the side shown in FIG. 4;

FIG. 7 is a cross sectional view taken along line 7-7 of FIG. 6. FIG. 8 is a side elevation view thereof, rotated 90 degrees from the side shown in FIG. 4;

FIG. 9 is a side elevation view thereof, rotated 135 degrees from the side shown in FIG. 4;

FIG. 10 is side elevation view thereof, rotated 180 degrees from the side shown in FIG. 4;

FIG. 11 is side elevation view thereof, rotated 225 degrees from the side shown in FIG. 4;

FIG. 12 is side elevation view thereof, rotated 270 degrees from the side shown in FIG. 4; and,

FIG. 13 is side elevation view thereof, rotated 315 degrees from the side shown in FIG. 4.
